(57) **CLAIM**

The ornamental design for an electric balance bicycle, as shown and described.

DESCRIPTION

FIG. 1 is a front elevational view of an electric balance bicycle showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and right side perspective view thereof; and, FIG. 8 is a rear and left side perspective view thereof.

The broken lines in the drawings illustrate portions of the electric balance bicycle that form no part of the claimed design.
